Specification of Letters Patent. Patented Apr. 20, 1920.

Application filed January 25, 1919. Serial No. 273,118.

To all whom it may concern:

Be it known that we, SAMUEL B. WILLIAMS, JR., residing at Brooklyn, in the county of Kings and State of New York, and FLORENCE DAVIS BALDWIN, administratrix, residing at Montclair, in the county of Essex and State of New Jersey, citizens of the United States, are in possession of an invention in a certain new and useful Improvement in Telephone-Exchange Systems, invented by the said SAMUEL B. WILLIAMS, JR., and CHARLES F. BALDWIN, deceased, of which the following is a full, clear, concise, and exact description.

This invention relates to an indicating system for telephone exchanges and has particularly to do with means for automatically informing the operator in a telephone call distributing system of the number and, if desired, the class of service of a calling line.

In a call distributing system, when a subscriber calls, his line is automatically extended to a connecting cord or circuit at an operator's position which happens at the time to be available for answering the call and completing the desired connection. In a system of this character it is desirable that the operator shall know the number and class of service of the calling line in order that she may be guided in making the charges for the completed connection and with respect to other duties she must perform. As the connection with the calling line in such a system is made by means of an automatic switch, and not by the operator directly, the operator is in ignorance of the number and class of service of the calling line unless special provision is made for conveying this information to her. It is the object of the present invention to provide a simple and effective organization for accomplishing this result.

In general, the plan of the present invention is to provide a number indicating device at the operator's position so arranged as to be brought into connection with any one of the operator's cord circuits to which a call is extended. Associated with each of the finder circuits that act to find and connect with calling lines, is an impulse sending switch arranged to send a series of groups of impulses that operate the number indicating device to indicate to the oper-

ator the number and class of service of the calling line. The impulse sending switch associated with the finder circuit sends consecutive groups of impulses corresponding in number to the thousands, hundreds, tens and units digits of the calling line, and also a final set of impulses arbitrarily chosen to indicate the class of service of the calling line.

As the impulse transmitting device is associated with a finder circuit that may operate to establish connection with any one of a large number of calling lines, means are provided for determining or automatically selecting the number of impulses in each group of the train transmitted so that the number of impulses in the consecutive groups may correspond with the digits in the number of the particular calling line with which the finder circuit happens to be connected. In the type of system in connection with which the preferred embodiment of the invention is illustrated, the finder circuit is connected with the calling line by means of a finder switch having a plurality of normally inactive brushes and a corresponding plurality of groups of line terminals with which the brushes respectively coöperate. When a line calls, the brush corresponding to the group of lines in which the calling line is located, is tripped and made active, and the switch is moved to bring the active brush into engagement with the calling line. In the present embodiment of the invention, therefore, the particular brush tripped indicates the line group in which the calling line is located, and the extent of movement of the switch in bringing the active brush into engagement with the calling line terminals indicates the number of the line in the line group that has been indicated by the particular brush tripped. In the system of this invention, the impulses for indicating the hundreds digits of the calling line are determined by the particular set of brushes tripped; the impulses for indicating the tens digits of the calling line are determined jointly by the particular brush tripped and the extent of movement of the switch in connecting with the calling line; and the impulses for indicating the units digits of the calling line are determined solely by the extent of move-

ment of the switch in making connection with the line. The impulses that indicate the thousands digits, for the reason that all of the lines served by any given finder switch are always in the same thousands group in the present embodiment of the invention, are determined by a permanent connection of the thousands terminal of the impulse transmitting switch with the appropriate commutator of the impulse producing device. As the class of service of the calling line has no relation to the directory number of the line, the impulses for indicating the class of service are obtained from a connection which is made through the finder switch with the calling line itself. In consequence of the above described arrangement, the impulse transmitting device associated with the finder circuit is adapted to send selective trains of groups of impulses that are automatically varied in accordance with the number and class of service of the line with which the finder switch makes connection; so that a single impulse transmitting device associated with the finder circuit serves to transmit to the number indicating device trains of impulses automatically varied in accordance with any line with which the finder switch has the capacity for making connection.

The preferred embodiment of the system of the invention is illustrated in the accompanying drawings, in which Figure 1 shows subscribers' circuits and the line finder switch; Fig. 2 shows an impulse sending switch; Fig. 3 shows circuits associated with the line finder switch; Fig. 4 shows a cord finder and a cord circuit associated with an operator's position, and Fig. 5 shows the construction of a switch as employed in the line finder.

In the above drawings the invention is shown as applied to a system such as is described in the previously filed application, Serial No. 229,035 (Case 36), filed April 17, 1918, of S. B. Williams, Jr. However, for the sake of simplicity, only so much of the circuits of the previously filed application are disclosed herein as seems to be necessary for an understanding of the present invention. Those parts of the circuits of the former application which are omitted, and their relation to the present invention, may be understood by referring to the previously filed application Serial No. 229,035, the same reference numerals being utilized as far as possible to designate similar parts in the systems of the present and the previously filed applications.

In the call distributing system illustrated in the drawings, two groups of calling lines are indicated, and one line of each of the groups is shown as extending to a subscriber's station, it being understood that the other lines are similarly connected.

There may be fifty lines in each line group, each line extending to a set of four terminals on a line finder switch LF. The line finder switch may be constructed to accommodate five hundred lines, ten groups of fifty lines each. Each of the groups of lines has associated with it a distributor switch 180, to the stationary contact terminals of which the lines of that group extend, the brushes of the distributor switch being connected with group apparatus which is actuated by the passage of the brushes over the terminals of a calling line. Each of the lines has associated with it a resistance coil 91, and each line is also provided with one or more spring jacks 14 by means of which connection may be made with the line when it is called. Each of the lines of the various groups may be connected with one of the commutators of a class-of-service and line number identifying interrupter 640, which may be common to the exchange.

The groups of lines have access to groups of connecting circuits or cord circuits CC through the medium of finder circuit F. These finder circuits terminate upon the brushes of pairs of finder and selector switches, one finder switch being diagrammatically illustrated and designated LF, and one selector switch being merely indicated at CS. Obviously the finder circuit may be connected with the connecting circuit in any well known way by switching means other than an automatic cord selector switch. The starting of the finder switch LF to find the calling lines is effected by the distributor switch apparatus through the medium of starting apparatus, including the relays 20, 23, 634 and 24, which is common to all of the line groups and to all of the finder circuits having access to the lines of these groups. There may be a number of groups of connecting circuits UC to which the lines of the various groups of lines have access by way of the finder circuit F, each group of connecting circuits being associated with a particular operator's position. Each connecting circuit may terminate in a plug 334 adapted for insertion in multiple spring jacks 339 of lines extending to subscribers' stations.

Each of the operators' positions is provided with apparatus which is common to all of the connecting circuits of that position, and which may be brought into association with any of the connecting circuits either automatically in the extension of a call to a connecting circuit, or at the will of the operator in the course of her supervisory operations. This apparatus common to the operator's position includes a number indicating device 700 which may be brought into connection with any connecting circuit to which a calling line has been extended, and which is selectively operated by means of

impulses of current transmitted by way of the finder circuit to indicate, by the illumination of certain ones of an associated bank of lamps 735, the number and class of service of the calling line.

The number indicating device may be of any suitable type adapted to respond selectively to trains of impulse groups or characteristic currents transmitted to it by the 10 impulse sending switch, and to display visual signals varying with the characteristic currents or trains of impulses received. One suitable form of indicating device is the device 700 shown in Fig. 4. This consists of 15 a shaft 710 which may be rotated through a pawl and ratchet mechanism by the quick acting magnet 705, and which may be elevated through a similar mechanism by the action of the slow release magnet 704. A 20 set of arms or brushes 711, 712, 717, 719 and 721 loosely mounted on said shaft are adapted to travel over rows of contacts of which there are ten in each row. Associated with each contact is a lamp 735, only the last 25 lamp of each row being shown. The arrangement is such that when a brush is moved to a particular contact, a circuit for the lamp individual to such contacts is partially established, which circuit is completed 30 when all of the arms are set through the contact 724 operated at the topmost position of the shaft 710. A yoke indicated at 736 is secured to the shaft 710 and carries a pawl 737, which in the lowermost position of the 35 shaft 710 engages a ratchet on the arm 721, and as the shaft is rotated, rotates such arm. In successive vertical positions of the shaft 710 the pawl 737 engages the other arms 719, 717, 712 and 711. After an arm has been 40 operated through the rotation of the shaft 710, it is held retained in its operated position by one of the holding pawls 713, 716, 718, 720 and 722. A pawl 740 controlled by the armature of the vertical stepping magnet 704 holds the shaft 710 in its rotated position until the shaft is stepped vertically, when such pawl is operated and permits the shaft 710 to be rotated back to normal by a suitable spring not shown. The holding 45 magnet 715 is energized before the indicator is set and is released when the indicator has performed its function. The release of this magnet withdraws the holding pawls 714, 713, 716, 718, 720 and 722 and restores all parts of the indicator to normal. The particular combination of lamps illuminated in any given case indicates to the operator the number and class of service of the calling line.

50 The impulses for selectively operating the indicating device 700 are applied to one of the conductors of the finder circuit, and through it to a corresponding conductor of the connecting circuit CC, by means of an impulse sending switch 620 (see Fig. 3) as-

sociated with the finder circuit. Each of these switches, there being one for each finder circuit, is provided with a series of as many stationary contacts as there are digits in the maximum line number in the 50 system, with an additional contact for controlling the class-of-service indication. In the present instance there are five stationary contacts, designated 621 to 625 inclusive. Coöperating with these contacts are three 55 arms or wipers 626 in fixed relation to each other, and so arranged that as one of the arms leaves the last contact of the series another arm engages the first contact. This is in order that the switch may always travel 60 in the same direction and to avoid the necessity of restoring it after it has performed its function. The arms are rotated by means of the intermittent energization and deenergization of a stepping magnet 630, 65 the pawl 631 being arranged to step the arms forward upon the release of the magnet. The ratchet wheel 633 engaged by the stepping pawl 631 is also engaged by a pawl 632 which acts to insure the movement of 70 the arm to a position where it is centered on a contact, and to prevent retrograde movement. The stepping magnet 630 is made slow to release, as by being provided with a copper jacket around its core. The 75 impulses that the impulse sending switch 620 applies to the number indicating device 700, pass through the stepping magnet 630; but as the interruptions between successive 80 impulses of each set or train are short, they 85 do not cause the stepping magnet 630 to release its armature, the release occurring only through a more protracted interruption at the end of each impulse train. This long 90 interruption of the circuit through the magnet 630 permits the armature to release, and thus step the arm 626 to the next contact in the series which the arm engages. The 95 impulse-sending device 620 is also provided with a series of contacts 628 engaged by a 100 set of arms 627, the arrangement being such that one of the arms engages the first contact of the series upon the first step that the switch takes from its normal position, and 105 disengages the last contact of the series upon 110 the last step which the switch takes.

The impulses that are applied to the number indicating device through the medium of the impulse sending switch 620, are produced by an identifying interrupter 640 120 (see Fig. 2). This interrupting device comprises commutators 641 to 650, inclusive, that are arranged to produce from one to ten interruptions, respectively and consequently from one to ten impulses of current for each 125 cycle of rotation. The interrupter 640 also is provided with a pick-up commutator 651 and a slip-ring 652, the pick-up commutator being geared to rotate once for each five rotations of the commutators 641 to 650 inclusive. To 130

simplify the drawing, certain of the commutators of the interrupter 640 are represented at different points in the drawing by circles with included numerals indicating the number of impulses of current produced by the commutator for each revolution.

An impulse selecting commutator controlled in accordance with the movement of the line finder elevator, and an impulse 10 selecting switch controlled in accordance with the particular set of brushes tripped and made active, operate singly or in conjunction in the selection of impulses for designating certain of the digits of the calling subscriber's line. The impulse selecting commutator is a part of the line finder switch LF which may be substantially like the switch illustrated and described in Patent 1,777,044 to James L. McQuarrie, issued 20 March 28, 1916. The structural arrangement of this switch is generally shown in Fig. 5, which illustrates diagrammatically portions of two of the brush carrying elevators and associated banks of multiple line 25 terminals of the panel type switch of the McQuarrie patent. Each finder switch comprises a longitudinally movable shaft 1, carrying as many sets of brushes 2 as there are groups of stationary line terminals to 30 be engaged, and in addition an impulse selecting commutator consisting of a set of brushes 2' and an associated group of stationary terminals comprising three vertical rows T, T' and U, with as many terminals 35 in each row as there are sets of terminals in a bank of line contacts. In the present instance, each bank of line terminals has fifty sets of terminals, and there are consequently fifty terminals or contacts in 40 each of the three rows engaged by the set of brushes 2'.

The brush carrying shaft 1, is moved up through the medium of an extension at the lower end of the shaft, which is brought 45 into engagement with the constantly rotating power member 3 by means of an idler wheel operated by the up-drive magnet 32; and the brush-carrying shaft is moved down by means of a reversely rotating power 50 member 4 with which the extension of the shaft is brought into engagement by means of an idler wheel operated by the down-drive magnet 62. Normally each of the brushes of each of the sets 2 are held apart 55 so as to clear the associated terminals by means of a separating cam 5 located between the innermost brushes of the set. The cam 5 is rotatably mounted, and when rotated in one direction, releases the brushes 60 and permits them to engage the associated line terminals. The brushes of the set 2' are fixedly mounted so as to engage the terminals in the rows T, T' and U of the associated contact bank as the brush-carrying 65 shaft moves up and down. The tripping

or releasing of the brushes of the brush sets 2 is controlled by a number of tripping magnets 17-1 to 17-10 inclusive. Each of these magnets when energized rotates an associated trip rod 6 that extends transversely of the switch shafts 1 and carries as many tripping yokes 7 as there are finder switch elevators in the group. The tripping rod in rotating brings all of its trip yokes 7 into position to operate the 75 brush-controlling cams 5 of the corresponding sets of brushes on all of the switches, so that whichever of the finder switches is caused to move up, has that set of brushes tripped that corresponds with the particular trip magnet 17-1 to 17-10 that is at the time energized. When the finder switch that has been in use is returned to its normal position, any of the associated controlling cams 5 that has been tripped, is engaged and rotated in a reverse direction to separate its switch springs again and thus render them inactive. Each of the line finder elevators also has associated with it a 80 commutator 8 which comprises a number of stationary commutator segments, and a set of movable brushes carried at the top of switch shaft 1 and co-operating with the stationary segments. This commutator serves to make and break a number of the 85 controlling circuits in the various stages of the movement of the switch shaft.

The stationary contacts engaged by the set of brushes 2' of the impulse selecting commutator correspond in number and location to the stationary contacts of each of the line groups, so that in any position to which the elevator is moved, the brushes of the set 2' are in engagement with contact terminals corresponding in position to the contact terminals simultaneously engaged by the active set of line brushes 2. The terminals of the rows T, T' and U are permanently connected with the various commutators of the interrupting device 640. 100 The first ten contacts of the row T are multiply connected to commutator 650 which supplies ten impulses of current during each rotation of the interrupter 640; the next ten terminals of row T are multiply connected to the commutator 641 which supplies one impulse of current during each 105 rotation of the interrupter; similarly, successive series of ten contacts in the row T are multiply connected to commutators 642, 643 and 644 which supply two, three and four impulses of current, respectively, in each rotation and successive series of ten contacts in the row T' are multiply connected to the commutators 645, 646, 647, 648 110 and 649 which supply five, six, seven, eight and nine impulses, respectively, in each rotation of the interrupter 640. Obviously in the rows T and T' each multiply connected series of ten contacts may be replaced by 115 120 125 130

a single contact of a length equal to the combined length in the row of the ten individual contacts of the corresponding series. In the row U of stationary contacts, 5 every tenth contact is multiply connected to the same commutator of the interrupter 640, the lowest contact of the row and the five other contacts to which it is multiply joined being connected with commutator 10 650 which delivers ten impulses per revolution, the second contact from the bottom and its multiply connected contacts being connected with commutator 641 which delivers one impulse of current per revolution. 15 20 25 30 35 40 45 50 55 60 65

and so on through the multiply connected series of contacts in the row. Each of the five series of ten contacts each, into which the row U is thus divided, is therefore arranged to deliver from one to ten impulses of current to the coöperating brush, depending upon the particular contact of the series with which the brush is in engagement. The U row and brush of the impulse selecting commutator control the selection of the impulses for designating the units digit of the calling line. The T and T' rows and their associated brushes, in conjunction with the impulse selecting switch, control the selection of the impulses for designating the tens digits of the calling line. The impulse selecting switch alone controls the selection of the impulses for designating the hundreds digit of the calling line.

This impulse selecting switch of which there is one for each finder circuit, may be a sequence switch 600, the extent of movement of which may be controlled in accordance with the group in which the calling line is located, and consequently the set of brushes that is tripped. The sequence switch 600 is adapted to be moved to and to rest in any one of ten impulse selecting positions, these being positions 2 to 11 inclusive.

The movement of the impulse selecting sequence switch 600 of whichever finder circuit is extended to a calling line, is under the control of the ten relays 16-1 to 16-10, inclusive, one being provided for each of the ten groups of lines and being energized in the energization of the associated brush tripping magnet of that group. When any one of these relays 16-1 to 16-10 inclusive is operated, it closes an energizing circuit for the motor magnet of the sequence switch 600, and also closes a locking circuit for itself which is controlled in contacts of the sequence switch 600. The locking circuit of relay 16-1 of the first group of lines is completed through contacts of the sequence switch 600 that are closed until sequence switch 600 passes beyond position $\frac{1}{2}$ of its movement, the sequence switch thus coming to rest in position 2. The locking circuit of relay 16-2 associated with the sec-

ond group of lines is completed through contacts that remain closed until the sequence switch passes beyond position $\frac{2}{2}$ of its movement, the relay therefore releasing to open the sequence switch energizing circuit and stop the sequence switch at position 3. In like manner, relay 16-3 is released to stop the sequence switch at position 4, relay 16-4 is released to stop the sequence switch at position 5, and so on, the energization of each relay 16 of the various line groups thus causing the impulse selecting sequence switch 600 to take a different setting.

Other contacts of the sequence switch 600 control the impulses applied by the impulse sending switch 620 in its hundreds sending position. Thus in positions 2 and 3 of sequence switch 600, to one of which positions the switch is moved when any line in the first two groups including lines 0 to 99 calls, the sequence switch connects the hundreds contact terminal 622 of the impulse sending switch 620 to the commutator of interrupter 640 that supplies ten impulses of current, adapted to display the 0 lamp of the number indicating device 700. In positions 4 and 5, to one of which the switch is moved when any line in the third and fourth groups, including lines 100 to 199, calls, the sequence switch connects the hundreds contact terminal of impulse sending switch 620 to the commutator that supplies one impulse of current to the number indicating device 700. In like manner in position 6 and 7, corresponding to a call in the two groups including lines 200 to 299, sequence switch 600 connects the hundreds contact of switch 620 to the commutator that supplies two impulses of current; in positions 8 and 9, corresponding to a call in the two groups including lines 300 to 399, it connects the hundreds contact to the commutator supplying three impulses of current; and in positions 10 and 11, corresponding to a call in the two groups including lines 400 to 499, it connects the hundreds contact to the commutator supplying four impulses of current. The above is on the assumption that the 500 lines served by the finder switch are the first five hundred lines of the thousand,—that is, lines 0 to 499. If the lines served are the second five hundred lines of the thousand, that is, lines 500 to 999, then the contacts of the sequence switch 600 are so connected as to apply five, six, seven, eight or nine impulses of current to the hundreds contact of the impulse sending switch 620, depending upon whether the sequence switch has been moved to its 2 or 3, its 4 or 5, its 6 or 7, its 8 or 9, or its 10 or 11 position.

Still other contacts of the impulse selecting sequence switch 600 coöperate in the control of the impulses applied by the im-

pulse sending switch 620 in its tens sending position. As the lines that terminate on the first, third, fifth, seventh and ninth groups of contacts of the finder switch are the first fifty lines of their respective hundreds in each case, their tens digits are 0, 1, 2, 3 and 4, respectively; and as the lines that terminate on the second, fourth, sixth, eighth, and tenth groups of contacts of the 10 finder switch are the second fifty lines of their respective hundreds in each case, their tens digits are 5, 6, 7, 8, and 9, respectively. In the movement of the impulse selecting 15 commutator comprising the vertical rows of contacts T, T' and U and their corresponding brushes t, t' and u, as has been described, the five groups of ten contacts each in the vertical row T are so connected to the interrupter commutators as to apply 20 ten, one, two, three, and four impulses of current respectively to their associated brush t, and the five groups of ten contacts each in the vertical row T' are so connected to the interrupter commutators as to apply 25 five, six, seven, eight and nine impulses of current respectively to their associated brush t. Consequently, the contacts of the impulse selecting sequence switch 600 are so arranged that when the sequence switch has 30 been moved to its 2, 4, 6, 8, or 10 position, as the result of a call in the first fifty lines of any of the hundreds, the tens contact 623 of the impulse sending switch 620 is connected to brush t of the vertical row T, 35 so that ten, one, two, three, or four impulses of current are applied, depending upon the extent of the vertical movement of the line finder elevator; while if the sequence switch has been moved to its 3, 5, 7, 9, or 11 position, 40 as the result of a call in the second fifty lines of any of the hundreds, the tens contact of the impulse sending switch 620 is connected to brush t' of the vertical row T', so that five, six, seven, eight or nine 45 impulses of current are applied, depending upon the extent of the vertical movement of the line finder elevator.

For controlling the circuits of the organization, there are employed a number of sequence switches which are shown at different 50 points and designated 200, 300 and 600, respectively. These sequence switches may be of the type disclosed in Patent 1,127,808, issued February 9, 1915, to Reynolds and 55 Baldwin. Each consists of an electro-magnetically controlled motor or driving mechanism and a number of associated switch cams. The switch cams associated with each of the sequence switches 200 are designated 60 201 to 210, 212 to 214, and 216 to 225, inclusive; those shown associated with each of the sequence switches 300 are designated 301 to 310 and 317 to 320, inclusive; and those associated with each of the sequence

switches 600 are designated 601 to 613, inclusive. To each of the contacts associated with the various sequence switch cams are applied certain numerals. These numerals in the case of the cams 201, 301 and 601 indicate the only position of the associated 65 sequence switch in which these particular contacts are open; the numerals applied to all of the other contacts of each sequence switch indicate the only positions of the particular sequence switch in which the associated contacts are closed. 70

The manner in which the line identifying devices coöperate with each other and with the associated parts of the organization in a telephone call distributing system to perform their functions will be fully explained 80 in the detailed description that follows. It will be assumed that the directory number of station A is 8301, and that the subscriber at this station, in initiating a call for another subscriber's station, takes his telephone receiver from its hook. The brushes 131, 132 and 133 of the distributor switch 130 are fixedly mounted on a common shaft 85 that is driven by a suitable source of power, 90 and are constantly rotating. They are thus successively bringing the cut-in relay 11 and the test relay 12 into momentary association with the various lines of the line group LG' which the distributor switch 130 95 serves, and in which the calling line 8301 is included. If a line is in use either as a calling line or as a called line, its sleeve conductor 53 is connected through relatively low resistance with battery of the 100 same potential as that to which the winding of the cut-in relay 11 is connected, as will hereinafter be explained. Consequently, when the distributor brush 133 engages the 105 sleeve terminal of such a line, the cut-in relay 11 remains inert. But when the distributor brush 133 engages the sleeve terminal of a line that is not in use, an energizing path is closed for the cut-in relay 11 by way of the brush 133 and the sleeve resistance 91. The test relay 12, therefore, is connected with the two line conductors 38 and 39 of each line that is not in use, and when it is thus connected with the conductors of the line extending to station A (line 115 number 8301) at which the telephone receiver has been removed from its switch hook, the test relay 12 attracts its armature and closes a circuit that extends from battery through the winding of relay 9 to 120 ground by way of the front contact and armature of relay 12. Relay 9 in operating closes a locking circuit for itself by way of its left-hand armature and contact, and the left-hand armature and back contact of 125 relay 10. The distributor brushes do not stop upon the terminals of the calling line, but continue their rotation, the result of

their engagement with the calling line terminals being in effect to record the call by energizing and locking up the relay 9.

The effect of recording the call upon the relay 9 is to cause the starting of one of the finder switches LF which serve the lines of this and the associated line groups. This is accomplished through the medium of a starting circuit, two of the conductors 57 and 58 of which are extended to the relays 19 of the various line groups LG⁴, LG⁷, etc. Assuming that the starting circuit is not in use at the time the call is recorded on the relay 9 of the line group LG⁷, the operation of this relay closes a circuit that extends from battery through the left-hand armature and back contact of relay 23, upper back contact and armature of relay 634, right-hand armature and back contact of relay 24, conductor 57, right-hand resting contact and switch spring of relay 19 of group LG⁷, the windings of relay 19 and the associated trip magnet 17-7 and relay 16-7 in parallel, left-hand switch spring and resting contact of relay 19, right-hand winding of relay 18, and right-hand front contact and armature of relay 9 to ground. The closure of this circuit causes relay 18 to operate; and in operating, relay 18 closes at its left-hand front contact and armature a shunt path by way of its left-hand low resistance winding to ground that sufficiently increases the current flow in the circuit to bring about the operation of the relay 19 and its associated trip magnet 17-7 and relay 16-7, the relatively high resistance of the right-hand winding of the relay 18 preventing the relay 19 and its associated trip magnet and relay from being operated at the initial closure of the circuit. Relay 19 in operating closes a circuit that extends from battery by way of the left-hand armature and back contact of relay 23, upper back contact and armature of relay 634, winding of the starting relay 24, conductor 58, the right-hand armatures and resting contacts of other relays 19 in the series, right-hand armature and switch spring of the relay 19 of group LG⁷, the windings of relay 19 and associated trip magnet 17-7 and relay 16-7 in parallel, and the left-hand switch spring and armature of relay 19 to ground. The closure of this circuit operates relay 24 and the trip magnet 17-7 of line group LG⁷ to start a line finder switch LF, and to trip the brushes of that switch which correspond with the line group in which the calling line is located; and also operates the associated relay 16-7 to control the movement of the impulse selecting sequence switch 600 of the finder circuit, all as will hereinafter be described. This circuit is maintained and the trip magnet 17-7, associated relay 16-7, starting

relay 24 and group relay 19 held energized 65 until the relay 23 is actuated at a later stage of the operation, as will be described.

When the recorded call has thus brought about the energization of the starting and brush-tripping circuit, the call recording apparatus, including the relays 18, 9 and 10, is disconnected from the starting circuit and the record obliterated by the releasing and return of these relays to their normal condition. When the recording apparatus obtains access to the starting circuit, the operation of the relay 18 not only brings about the energization of the starting and tripping circuit, by closing at its left-hand front contact and armature the 70 low resistance path to ground; but it also closes a circuit that extends from battery through the winding of relay 10, and the right-hand front contact and armature of relay 18 to ground. The closure of this 75 circuit causes relay 10 to open, at its left-hand back contact and armature, the locking circuit of the relay 9. Relay 9 in releasing opens at its right-hand front contact and armature, the path to ground by 80 way of the right-hand or high resistance winding of the relay 18. As relay 19 in operating has opened at its left switch spring and resting contact, the main energizing circuit of the relay 18, relay 18 therefore 85 releases, and in doing so opens at its right-hand front contact and armature the energizing circuit of the relay 10, which relay thereupon releases. Thus the relays 18, 9 and 10 of the recording apparatus are 90 returned to normal and are in readiness to respond to another calling line.

As has been described, the appropriation of the starting circuit by an incoming call is accompanied by the operation of the relay 24, and the relay 24 in operating disconnects the conductor 57 from battery. As it is over this path from battery that the initial energization of any of the relays 19 is effected, the calling lines of the 105 other groups are deprived of control over their associated relays 19, trip magnets 17 and associated relays 16 until the starting relay 24 is returned to normal and the path to battery closed. If a line in another group, say group LG⁴, calls while the relay 24 is serving the calling line of group LG⁷, the recording relay 9 of that other group is locked up and holds 110 closed a path to ground from conductor 57, 115 by way of the right hand winding of the associated relay 18, that includes the winding of the associated relay 19, trip magnet 17-4 and relay 16-4 in parallel. When the starting relay 24 has performed its 120 function in connection with the calling line of group LG⁷ and releases its armatures, the relays 23 and 634 also being inert at

the time, the path by way of conductor 57 is completed for the energization of the relays 18, 19 and 10 and the trip magnet 17-4 and relay 16-4 of group LG⁴ in the 5 manner that has been described in connection with the operation of these devices in group LG⁷.

When the common starting relay is energized in response to a call in one of the 10 groups, as described above, it closes a circuit that extends from battery by way of the cord selector sequence switch contact 320 (1 to 4) of whichever of the line finder switches LF is next in order to be started, 15 winding of relay 30, selector sequence switch contact 309 (1 to 7), finder sequence switch contact 217 (2), and thence to ground by way of conductor 29 and the left hand armature and front contact of starting relay 24. Relay 30 in operating closes a circuit that extends from battery through the motor magnet and contact 203 (2) of the 20 finder sequence switch, and right-hand front contact and armature of relay 30 to ground. 25 The closure of this circuit moves the finder sequence switch 200 out of position 2. Relay 30 in operating also closes a locking circuit for itself that extends from battery by way of selector sequence switch contact 320 (1 to 4), winding of relay 30, selector sequence switch contact 309 (1 to 7), left-hand front contact and armature of 30 relay 30, selector sequence switch contact 317 (1), finder switch sequence contact 216 (2 to 4), conductor 25, and the right hand back contact and armature of relay 23 to ground. When the finder sequence switch moves from position 2 to position 3, it 35 closes a circuit from battery through the winding of up-drive magnet 32, conductor 59, finder sequence switch contact 213 (3 to 4) and the right-hand back contact and armature of test relay 37 to ground, that starts the upward movement of the elevator shaft 1 carrying the sets of brushes. 40 The test relay 37 is energized to open the circuit of the up-drive magnet 32 and stop the upward movement of the finder switch brushes when the terminals of the calling 45 line are engaged, as will hereinafter be described.

At the outset of the upward movement of the elevator shaft 1 of the line finder switch, as a result of the energization of the up- 55 drive magnet 32, all of the brush trip levers are moved past their corresponding trip yokes 7 (see Fig. 5). The only trip magnet that is in its energized condition in this case is the magnet 17-7 which corresponds 60 with the group LG⁷ in which the calling line is assumed to be located; and consequently the only trip yoke in position to engage a trip lever on the elevator shaft is the one which controls the brushes 40, 41, 42 65 and 43 that are adapted to engage the termi-

nals of that particular group of lines. This set of brushes, therefore, is released and made operative, and the other sets are held clear of their associated line terminals.

At the same time that the trip magnet 17-7 is energized to determine the tripping of the corresponding set of brushes, the associated relay 16-7 is energized to determine the setting that the impulse controlling sequence switch 600 shall take. When the relay 16-7 is operated by the flow of current through its right-hand winding that occurs when the relay 19 of the corresponding group operates, and when, an instant later a finder circuit has been set in operation to 75 take the call, a circuit is closed that extends from battery through the left-hand winding and the inner front contact and armature of relay 16-7, conductor 666, multiple branch to contact 610 (1 to 7½) of the impulse selecting sequence switch of the chosen finder circuit, and to ground by way of contact 225 (3) of the finder sequence switch 200. This locking circuit of relay 16-7 is thus maintained subject to the control of the impulse 80 selecting sequence switch 600. When relay 16-7 operates it also closes a circuit that extends from battery through the motor magnet of the impulse selecting sequence switch of the chosen finder circuit, finder 85 sequence switch contact 222 (3), conductor 638, outer front contact and armature of the operated relay 16-7, through the back contacts and armatures of the other relays 16 preceding the relay 16-7 in the series, conductor 636, and finder sequence switch contact 225 (3) to ground. The closure of this circuit energizes the motor magnet of sequence switch 600, and causes that sequence switch to rotate until its energizing circuit is 90 opened. The opening of the circuit occurs when the relay 16-7 becomes deenergized, and this takes place when the locking circuit of relay 16-7 by way of the left-hand winding of the relay is interrupted at contact 610 (1 to 7½) of the impulse selecting sequence 95 switch, this occurring when sequence switch 600 has moved beyond position 7½. 100 The impulse selecting sequence switch therefore stops in position 8, in which position the hundreds contact 622 of the impulse sending switch 620 is connected, by way of sequence switch contact 607 (8 to 9), with the commutator of interrupter 640 that delivers three impulses of current in each cycle 105 of rotation. As position 8 of the sequence switch 600 is one of the even numbered positions in which the switch is adapted to rest, the tens contact 623 of the impulse sending switch 620 is connected by way of the sequence switch contact 605 (8) and conductor 653 with brush *t* that cooperates with the vertical row T of the impulse selecting commutator. As will subsequently be described, 110 the line finder elevator, in connecting with 115 the line 120

the calling line, which is assumed to be line number 8301, is stopped on the second set of terminals of the fifty sets in the bank on which the calling line terminates. Therefore brush t is stopped on the second terminal in the vertical row T, which terminal, together with the nine other terminals of the first ten in the row, is connected with the commutator of interrupter 640 which delivers ten impulses of current per cycle; and consequently this commutator is connected to the tens terminal of the impulse sending switch 620.

As soon as the set of brushes corresponding with the group in which the calling line is located in tripped, the trip magnet 17-7 and the relay 19 of this group and the common starting relay 24 are released. The release of the trip magnet and its associated group relay 19 and the starting relay 24 is effected by the closure of a circuit which extends from battery by way of the winding of relay 23, conductor 26, finder sequence switch contact 212 (3 to 4), conductor 68, and segment G of the line finder commutator and its corresponding brush to ground. As a result of the closure of this circuit, which is timed to occur an instant after the brushes are tripped and before they engage the line terminals in the upward movement of the elevator shaft, relay 23 is energized to open, at its left-hand armature and back contact, the circuit by way of conductor 58 that up to this time has been holding the starting relay 24, the trip magnet 17-7 and the associated relay 19 energized. The relay 23 in operating also closes at its right-hand armature and front contact an energizing circuit for the relay 634, and this relay at its upper armature and back contact introduces another break into the circuit that supplies battery to the starting relay 24, group relay 19 and trip magnet 17-7, and also closes at its lower front contact and armature a locking circuit for itself that extends by way of conductor 635 and finder sequence switch contact 225 (3) to ground. This insures the maintaining inoperative of the starting relay 24 and the relays 19 and 16, and the trip magnet 17 of the other groups until the sequence switch 200 of the seized finder circuit moves out of position 3.

When relay 23 operates, in response to the grounding of the G segment of the line finder switch commutator, it also interrupts at its right hand armature and back contact the previously traced circuit that has maintained relay 30 of the finder circuit energized. That relay, in releasing its armatures, closes a circuit for moving the finder sequence switch 200 of some other finder circuit from its normal or first position to position 2, where it is in readiness to respond to the next operation of the

starting relay 24. Assuming that the finder circuit F', which may be assumed to be similar to the finder circuit F in its equipment, has its parts in their normal condition, this circuit may be traced from battery through the motor magnet 200 and contact 204 (1) of the finder circuit F', finder sequence switch contacts 204 (5 to 18) of other finder circuits similar to the circuits F and F' in their equipment, which finder circuits may be assumed to be busy, and therefore to have their sequence switches in some position between position 5 and position 18 inclusive, finder sequence switch contact 221 (3 to 4) of finder circuit F, left-hand back contact and armature of relay 30, selector sequence switch contact 317 (1), finder sequence switch contact 216 (2 to 4), conductor 25, and right-hand back contact and armature of relay 23 to ground.

Thus the passing of the G segment in the upward movement of the started finder switch releases the group and starting relays and trip magnet, releases relay 30 of the associated finder circuit, and moves sequence switch 200 of another finder circuit into position 2 in readiness to respond to the next actuation of the starting relay 24 as soon as the starting circuit is again made effective by the movement of the first finder sequence switch out of position 3 and the release of relay 634.

When the impulse selecting sequence switch 600 moves beyond position $7\frac{1}{2}$ and opens the locking circuit of 16-7, as previously described, that relay not only opens the energizing circuit at the sequence switch and stops the movement of the switch, but it also closes at its outer armature and back contact a circuit that extends from battery through the motor magnet and contact 224 (3) of the finder sequence switch, conductor 637, the back contacts and armatures of all of the 16 relays in series, including the back contact and armature of relay 16-7 just released, conductor 636, and finder sequence switch contact 225 (3) to ground. The closure of this circuit moves the finder sequence switch out of position 3, the switch coming to rest in position 4. This movement of the finder sequence switch out of position 3, which occurs when the impulse selecting sequence switch has completed its registration of the calling line group, breaks the locking circuit of relay 634 and releases that relay, thus rendering the starting circuit again available for the use of another calling line.

The condition that is now assumed to exist is one in which the line finder switch LF is moving up with its set of brushes tripped corresponding with line group LG', in which the impulse selecting sequence switch 600 has been moved to position 8, corresponding with the group in which the calling line

is located, and in which the finder sequence switch of another finder circuit F' has been moved to position 2 in readiness to respond to the next operation of the starting relay. 5 As the tripped brushes rise, they come into engagement consecutively with the sets of terminals corresponding with the different lines of the group. At the instant of engagement of the brush 42 with the corresponding terminal 46 of each line, a circuit 10 is closed that extends from battery by way of relay 52 (see Fig. 3), sequence switch contact 209 (2 to 4), conductor 50, brush 42, line terminal 46, conductor 53, and resistance 15 91 to ground. In case a line is busy, either as a calling line or as called line, a path to battery extends from conductor 53, as will hereinafter appear, that serves to shunt the relatively high resistance relay 52 and 20 prevent its operation. If a line over the terminals of which the brushes are passing is not busy, the relay 52 is operated, and in attracting its armatures closes a circuit that extends from battery through the left-hand 25 winding of the relay 37, inner armature and front contact of relay 52, sequence switch contact 208 (2 to 4), line terminal 45, conductor 39 to one limb of the telephone line, thence by way of the path controlled in contacts of the substation switch hook to the other limb of the line, conductor 38, terminal 44, brush 40, conductor 48, sequence switch contact 207 (2 to 4), outer front contact and armature of the relay 52, and right- 30 hand winding of the relay 37 to ground. The circuit traced above is not completed until the finder switch brushes engage the terminals of the calling line, as the calling line is the only line that has its telephone 35 receiver off the hook, and at the same time is not connected with either by some other line finder or by a connecting circuit calling plug. The completion of this circuit energizes the relay 37 and causes that relay to 40 interrupt at its left-hand back contact, the circuit, by way of the finder sequence switch contact 213 (3 to 4) and conductor 59, which up to this time has been keeping the updrive magnet 32 energized to cause the 45 upward movement of the switch brushes; therefore the operation of the relay 37 upon the finding of the calling line acts to effect the instant deenergization of the updrive magnet 32 and thus to stop the line brushes 50 on the terminals of the calling line and the brushes *t*, *t'* and *u* upon corresponding terminals of the impulse selecting commutator.

Relay 37, in operating, also closes a locking circuit for itself by way of its left-hand front contact and armature and finder sequence switch contact 219 (3 to 4) to ground. It also completes a circuit that extends from battery through the motor magnet and contact 56 (4) of the finder sequence switch,

and right-hand front contact and armature of relay 37 to ground. If the impulse selecting sequence switch 600 has completed its registration of the calling line group, and the consequent release of relay 16—7 70 has moved the finder sequence switch 200 out of position 3, as previously described, the closure of the circuit at the right-hand front contact and armature of relay 37 moves the finder sequence switch out of position 4. But if the line brushes of the line finder switch reach the terminals of the calling line before the group registration on the impulse selecting sequence switch 600 is completed, then the circuit closed by way 75 of the right-hand front contact and armature of relay 37 remains in readiness to move the finder sequence switch out of position 4 as soon as the completion of the group registration moves the finder sequence switch 80 out of position 3.

When the finder sequence switch moves to position 5 as a result of the finding of the calling line, it closes a circuit that extends from battery by way of resistance coil 54 90 and sequence switch contact 210 (5 to $5\frac{1}{2}$), the sleeve conductor 50 of the finder circuit, and thence by way of the finder switch to the sleeve conductor 53 of the calling subscriber's line. This creates an electrical condition upon the line that prevents it thereafter from affecting the distributor test magnets 11 and 12, and that prevents it from being connected with by any other line. In moving to position 5, the finder sequence 100 switch also closes a circuit that extends from battery through the motor magnet and contact 302 (1) of the selector sequence switch, contact 220(5), of the finder sequence switch, and right-hand back contact and armature 105 of relay 37 to ground, the relay 37 having been released by the breaking of its locking circuit when the finder sequence switch moves out of position 4. The closure of this circuit moves the selector sequence switch 110 out of position 1 and into position 2.

After the calling line has been extended to a finder circuit, in the manner described in the foregoing, the finder circuit is extended to an idle connecting circuit or cord on an operator's position, that is at the time available for handling the call and completing the connection of the calling line with the called line. The precise manner in which the finder circuit is extended to an operator's 115 connecting cord is immaterial to the present invention, and may be accomplished in any one of a number of well-known ways. In the present instance, the finder circuit is illustrated as extending in four conductors, 120 96, 97, 98 and 99, to four corresponding brushes of a switch CS which may be the cord selector switch of the previously mentioned application, Serial Number 229,035, (Case 36,) filed April 17, 1918, by S. B. 125 130

Williams, Jr. The four brushes of the cord selector switch are adapted to extend the finder circuit to a cord circuit CC by their engagement with the terminals 115, 116, 117 and 118 of that cord circuit. There may be 5 a plurality of such cord circuits, and these cord circuits may terminate at a plurality of operators' positions. The apparatus shown associated with the right-hand half 10 of the finder circuit corresponds with a part of the finder circuit apparatus of the above mentioned application of S. B. Williams, Jr.; but only as much of the apparatus is here shown as is required to indicate the 15 connection of the finder circuit conductors with the connecting cord circuit through the medium of the selecting switch CS. The selector sequence switch 300 has an energizing circuit whereby it may be moved from one 20 to another of its operating positions. When it arrives in position 7, the brushes of the cord selecting switch CS are in engagement with the terminals of the selected cord, and a circuit is closed that extends from battery 25 by way of selector sequence switch contact 320 (7 to 11), winding of relay 30, selector sequence switch contact 305 (7 to 7½), conductor 99, brush 114 and contact 118 of selector switch CS, and closed contact 413 to 30 ground. Relay 30, in operating, closes a circuit that extends from battery through the motor magnet and contact 302 (6 to 8) of the selector sequence switch, and right-hand front contact and armature of relay 30 to 35 ground. This moves the selector sequence switch out of position 7 and into position 8. In moving out of position 7 the energizing circuit of relay 30, traced above, is broken at selector sequence switch contact 305 (7 to 40 7½), and relay 30 consequently releases its armatures. The movement of the selector sequence switch out of position 7 also breaks a locking circuit for relay 30, which was completed when that relay operated, by way 45 of selector sequence switch contact 309 (1 to 7), left-hand front contact and armature of relay 30, and selector sequence switch contact 310 (7) to ground.

When the selector sequence switch moves 50 into position 8, the impulse sending switch 620 associated with the finder circuit is connected with the number indicating device 700 associated with the connecting cord circuit, and the impulses that have been pre- 55 determined by the operation of the finder circuit mechanism are transmitted to the number indicating device to cause that device to display signals before the operator informing her of the number and class of 60 service of the calling line. The closure of the impulse transmitting circuit is under the control of the pick-up commutator of the interrupter, the arrangement being such that the circuit may be closed only at the 65 beginning of a series of cycles of rotation

of the interrupter in order that the trains of impulses that are transmitted may not be mutilated. The extension of the finder circuit to the connecting cord circuit is accompanied by the closure of the contacts 70 408, 411 and 416. At the beginning of the first cycle of rotation of the interrupter 640, after these contacts are closed, a circuit is completed that extends from battery 75 through the winding of relay 129, the upper back contact and armature of relay 155, contact 416, and pick-up commutator 651 to ground. Relay 129 attracts its armature and closes a path to ground by way of the winding of relay 155 and contact 80 411. While the path to ground by way of the pick-up interrupter 651 is closed, the path to ground by way of the relay 155 is short circuited. But an instant later, when the brush and conducting segment of 85 the pick-up interrupter 651 break contact, the relay 155 is energized by the current that flows through it by way of the winding of relay 129, this current also serving to lock up the relay 129. The relay 156 90 has been energized, by way of the upper back contact and armature of relay 157 and closed contact 411, by the extension of the finder circuit to the cord circuit. Therefore, when the relay 155 attracts its armatures, immediately upon the breaking of 95 circuit through the pick-up interrupter 651, a circuit is closed that extends from battery through the quick-acting rotary magnet 705, the slow-releasing vertical magnet 100 704, and the resting contact and switch spring 706 of the number indicating device, lower front contact and armature of relay 155, front contact and armature of relay 156, closed contact 408, terminal 118 105 110 and corresponding brush 114 of the cord selector, selector sequence switch contact 305 (8 to 9), stepping magnet 630 of the impulse sending switch 620, arm 626 and thousands contact 621 of that switch, 115 contact 608 (2 to 11) of the impulse selecting sequence switch, and the eight impulse per cycle commutator (648) of the interrupter 640 to ground. It will be observed that the conducting segments of all of the 120 impulse transmitting commutators of the interrupter 640, with which the respective brushes are in engagement at the start of each cycle of rotation, are relatively long segments. Therefore, the current that flows over the path just traced is of sufficient duration to cause the slow-acting magnets 630 of the impulse sending switch 620 and 704 of the number indicating device 700 to attract their armatures.

Having attracted their armatures, the slow acting magnets 630 and 704 hold them attracted during the series of short interruptions of the circuit which follow, and release them only upon the relatively long 130

break in the circuit at the end of the cycle. But the quick acting rotary magnet 705 of the number indicating device, attracts its armature at each make and releases it at 5 each break of the circuit; and each time the armature of the magnet is released, the pawl 708, acting through the medium of the cylindrical ratchet 709, moves the arm with which the pawl 737 is in engagement 10 on step ahead. Each step that an arm takes is retained by the corresponding holding pawl 722, 720, 718, 716, or 713, these pawls being dropped into engagement with the ratchet wheels, carried on the respective 15 arms by the energization of the release magnet 715 as a result of the closure of the circuit of this magnet at contact 411. As the circuit at present in question is opened and closed eight times in a single 20 cycle of rotation of the commutator 648, the arm 721 which the rotary stepping pawl engages, will be advanced to the eighth contact of the lower row of contacts. The last interruption of the circuit effected by 25 commutator 648 is long enough to permit the slow releasing magnets 630 of the impulse sending switch and 704 of the number indicating device to release their armatures. Magnet 630, in releasing, moves the 30 arm 626 into engagement with the hundreds contact 622, and the arm 627 into engagement with the first of a series of grounded contacts 628. Magnet 704 of the number indicating switch in releasing raises 35 the shaft 710 vertically one step, thus moving the pawl 737 out of engagement with the first arm 721 and into engagement with the second arm 719 of the series. At the same time the latch, depending from the 40 armature of the magnet 704, lifts the pawl 740 from the cylindrical ratchet 709 and permits the shaft 710 to turn back to normal. This places the number indicating device 700 in position to move the second arm 719 45 over its row of contacts in accordance with the number of impulses in the second train that is received.

As the impulse sending switch 620 has brought its arm 626 into engagement with 50 contact 622, the energizing circuit for the rotary magnet 705, and vertical magnet 704 of the indicating device, and the stepping magnet 630 of the impulse sending switch in series is now completed, under the assumption that it is line 8301 that is calling, 55 by way of arm 626, contact 622, contact 607 (8 to 9) of the impulse selecting sequence switch and to ground by way of the commutator of interrupter 640 that makes and 60 breaks the circuit three times in one cycle of rotation. The three interruptions of the circuit cause arm 719 of the number indicating device to be advanced to the third contact of the second row; and as a result

of the relatively long duration of the third 65 or last interruption, magnet 704 of the indicating device releases its armature and raises the shaft 710 another step to bring the pawl 737 into operative relation with the third arm 717; and the stepping magnet 70 630 of the impulse sending switch releases its armature and thereby advances the arm 626 another step to bring it into engagement with the contact 628.

This closes the operating circuit of the 75 number indicating device 700 and the impulse sending device 620 to ground by way of arm 626, contact 623, contact 605 (8) of the impulse selecting sequence switch, conductor 653, brush *t*, the second contact of 80 row *T*, and commutator 650, which is adapted to make and break the circuit ten times in one cycle of rotation of the interrupter. As a result of the ten breaks in the circuit, arm 717 of the number indicating 85 device is advanced to the tenth or naught contact of its row; and as the last break is a long one, the magnet 704 releases to elevate the shaft 710 another step, thus placing the fourth arm 712 in operative relation 90 with the rotary magnet 705, and magnet 630 of the impulse sending device releases to move arm 626 into engagement with contact 624. This completes the operating circuit of the indicating device 700 and the 95 impulse sending switch 620 to ground by way of arm 626, contact 624, contact 604 (2 to 11) of the impulse selecting sequence switch, conductor 655, brush *u*, the second contact of the corresponding row *U*, and 100 commutator 641, which is adapted to make and break the circuit once per revolution. The single long make energizes magnets 705 and 704 of the number indicating device and magnet 630 of the impulse sending 105 switch; and the relatively protracted break which follows, releases all three magnets, the release of magnet 705, advancing arm 712, into engagement with the first contact of its row, and the slower release of magnets 704 and 630, respectively, elevating the shaft 710 another step to bring arm 711 into operative relation with the rotary magnet 705, and advancing arm 626 of the impulse sending switch 620 into engagement with 110 contact 625.

This completes the operating circuit of the indicating device 700 and the impulse sending switch 620 by way of arm 626, contact 625, contact 318 (8 to 9) and (8 to 11) of the selector sequence switch, conductor 51, brush 43 and corresponding contact 47 of the finder switch LF, conductor 54 of calling line 8301 and to ground by way of the commutator of interrupter 640, that is 115 adapted to make and break the circuit four times per revolution. Consequently, the rotary magnet 705 of the indicating device 120

125

- extends from battery through the motor magnet and contact 304 (9) of the selector sequence switch, and right-hand back contact and armature of relay 30 to ground.
- 5 The closure of this circuit moves the selector sequence switch out of position 9 and into position 10.
- In position 10 of the selector sequence switch, a circuit is closed that extends from battery through the motor magnet and contact 202 (5) of the finder sequence switch, and contact 310 (10) of the selector sequence switch to ground. When the finder sequence switch moves out of position 5 and 10 into position 6, as a result of the closure of this circuit, it completes, at its contacts 207 (5½ to 6) and 208 (5½ to 6), the talking conductors of the finder circuit. When the selector sequence switch moves into position 15 10, it also closes a circuit that extends from battery through the winding of relay 13 (see Fig. 4), contact 412 and front contact and armature of relay 13 in parallel, the contact 412 having been closed when the 20 finder circuit was first extended to the connecting cord circuit, closed contact 81, contact 117 and brush 113 of the cord selecting switch CS, conductor 98, selector sequence switch contact 307 (10 to 11), left-hand 25 winding of relay 56, selector sequence switch contact 306 (8 to 11), finder sequence switch contact 209 (5½ to 6), conductor 50, thence by way of the finder switch to conductor 53 of the calling line, and to ground 30 through resistance 91. When relay 56 operates, as a result of the closure of this circuit, it closes a circuit that extends from battery through selector sequence switch contact 320 (7 to 11), winding of relay 30, 35 selector sequence switch contact 309 (10 to 11), and left-hand switch spring and armature of relay 56 to ground. Relay 30, in operating, closes a circuit that extends from battery through the motor magnet and contact 302 (10) of the selector sequence switch, and right-hand front contact and armature of relay 30 to ground. This 40 moves the selector sequence switch out of position 10 and into position 11, which is 45 the talking position of the switch.
- When the operator has obtained from the indicating device 700 the number and class of service of the calling line, the switches 408, 411 and 416 are opened to disconnect 50 the indicating device and permit its return to normal. In opening contact 411, the energizing circuit of the release magnet 715 is interrupted. The release magnet, therefore, releases its armature, which acts to 55 withdraw the holding pawl 714 to allow the shaft 710 to drop back to normal, and also to withdraw the pawls 713, 716, 718, 720 and 722 that hold the corresponding switch arms in the positions to which their respective 60 sets of impulses have advanced them. The dropping of the shaft 710 restores the switch springs 706 and 724, and the opening of contact 411 releases relays 155 and 157. The number indicating device and its controlling circuits are thus restored to their normal condition.
- In the extension of the finder circuit to the connecting cord circuit the switches 403, 404, 405 and 406 are operated to bring the operator's telephone set (not shown) into circuit with the calling line. Upon learning the number of the line desired, the operator completes connection with it by inserting the calling plug 334 into the spring jack 339, and operates the key 330 to apply ringing current from the generator 199. The supervisory relays 331 and 332, in connection with their associated apparatus (not shown), perform their usual function of informing the operator of the condition of the connection between the two telephone lines. When the disconnect signal is received, the plug 334 is withdrawn from the called line spring jack, and the closed contacts 81 are opened. The breaking of these contacts interrupts the flow of current through the relay 56 (see Fig. 4), and that relay in releasing its armatures opens, at its left-hand armature and switch spring, the energizing circuit for relay 30 that has been maintained during the conversation by way of selector sequence switch contact 309 (10 to 11). Relay 30, in releasing, closes a circuit that extends from battery through the motor magnet and contact 304 (11) of the selector sequence switch, and the right-hand back contact and armature of relay 30 to ground. This moves the selector sequence switch out of position 11.
- When the selector sequence switch reaches position 12, it closes a circuit that extends from battery through the motor magnet and contact 202 (6) of the finder sequence switch, and contact 310 (12 to 17) of the selector sequence switch to ground. As a result, the finder sequence switch moves out of position 6 and continues to move until it reaches position 17, at which time a circuit is closed that extends from battery through the winding of the down-drive magnet 62, conductor 60, and finder sequence switch contact 218 (17) to ground. This returns the line finder elevator to normal; and when the elevator has reached the limit of its downward movement, a circuit is closed that extends through the motor magnet and contact 203 (17) of the finder sequence switch, conductor 69, and segment Y and corresponding brush of the line finder commutator to ground. When the finder sequence switch is moved to position 18 in response to the closure of this circuit, a circuit is closed that extends from battery through the motor magnet and contact 602 (2 to 18) of the impulse selecting sequence switch 600, and

attracts and releases its armature four times, and advances arm 711 into engagement with the fourth contact of its row.

On the long break which is the last interruption of the series, the signals which have been selected as a result of the operation of the indicating device are displayed, the impulse transmitting switch is moved into normal position in readiness to transmit other sets of impulses, and the talking condition of the finder circuit is established, as will now be described. When the vertical stepping magnet 704 of the indicating device releases at the last long break, it elevates the shaft 710 another step. This causes the top 723 of the shaft to engage and operate the switch springs 706 and 724. The switch spring 706, in operating, interrupts the energizing circuit including the magnets 704 and 705 so that no more impulses may be transmitted through these magnets until the indicating device is restored at a later stage of the operation. The switch spring 724, in operating, closes a circuit that extends from battery in parallel through the various lamps that have been selected, the switch contacts corresponding to these lamps and the associated switch arms, switch spring 724 and its upper contact, and the lower front contact and armature of relay 157 to ground when this relay operates. The operation of the relay 157 occurs upon the closure of the pick-up commutator 651, which takes place once in each five revolutions of the interrupter 640. When the pick-up commutator closes at the end of the transmission of the train of five groups of impulses, as described, a circuit is completed that extends from battery through relay 157, upper switch spring and resting contact of that relay, upper front contact and armature of relay 155, closed contact 416, and pick-up commutator 651 to ground. Relay 157, in operating, closes at its lower front contact and armature the circuit already traced for the illumination of the selected lamps 735; and also closes a locking circuit for itself by way of its upper switch spring and armature, and closed contact 411 to ground. Relay 157, in operating, also opens at its upper back contact and armature the energizing circuit of the relay 156, so that that relay releases its armature and opens at another point the energizing circuit for the operating magnets of the indicating device, which circuit is also opened at switch spring 706 and resting contact of that device.

The lamps that are illuminated when the shaft 710 takes its last upward step and the pick-up commutator operates relay 157, are the eighth lamp of the first row, the third lamp of the second row, the tenth or zero lamp of the third row, the first lamp

of the fourth row, and the fourth lamp of the fifth row. The lamps of the number bank may be provided with caps upon which appear their respective numbers. Therefore, under the conditions assumed, the number 83014 is displayed before the operator, the first four digits being the number of the calling line and the last digit indicating the class of service of the line. Or, if desired, the class of service may be represented by a letter, or combinations of letters, on the lamp caps of the top row; and if the fourth lamp of the row is the one that is illuminated when the calling line is a "message rate" line, the letters MR may appear on the cap of this lamp.

The effect on the impulse sending switch 620 of the long interruption at the end of the last group of impulses is to cause the stepping magnet 630 to release its armature and move its switch arms ahead another step. This moves the switch arm 626 that has been active, out of engagement with contact 625, and brings another switch arm 626 into engagement with contact 621. It also moves the switch arm 627 that has been active, out of engagement with the last contact of row 628, and moves another switch arm 627 into position to engage the first contact of row 628 upon the first step that the switch may subsequently take. The impulse sending switch 620 is thus again in its normal position.

When the impulse sending switch took its first step in sending the trains of impulses, as described, it completed a circuit that extended from battery by way of selector sequence switch contact 320 (7 to 11), the selector sequence switch at the time resting in position 8, winding of relay 30, selector sequence switch contact 309 (8 to 9), and arm 627 and the first contact 628 of the associated row to ground. This caused relay 30 to attract its armatures and close a circuit extending from battery through the motor magnet and contact 302 (8) of the selector sequence switch, and right-hand front contact and armature of relay 30 to ground. The closure of this circuit moved the selector sequence switch 300 out of position 8 and into position 9. But this movement of the sequence switch did not disturb the circuit over which impulses were being transmitted from the impulse sending switch 620 to the number indicating device 700, because these circuits are closed at sequence switch contacts 305 and 318 in both positions 8 and 9 of the switch. When the impulse sending switch 620 takes its last step, and moves the arm 627 out of engagement with the last grounded contact 628 of the associated row, the energizing circuit of the relay 30 is broken, and that relay, in releasing its armatures, closes a circuit that

contact 223 (18) of the finder sequence switch to ground. The closure of this circuit moves the sequence switch 600 out of the position to which it has been advanced 5 in identifying the group of the calling line, and returns it to its 1 or normal position. At that time a circuit is closed that extends from battery through the motor magnet and contact 203 (18) of the finder sequence 10 switch, and contact 603 (1) of the impulse selecting sequence switch to ground. This moves the finder sequence switch out of position 18 and returns it to its normal or 1 position. All of the line connecting apparatus, 15 as well as the line number and class of service identifying apparatus, is thus returned to its normal condition.

In showing the preferred embodiment of the invention in connection with a call distributing system, it has been necessary to disclose a number of features which do not form a part of the present invention, and which are the subject of claims presented in the application of S. B. Williams, Jr., Serial 25 No. 229,035, filed April 17, 1918, hereinbefore referred to. It will be understood that this is only one of the systems to which the present invention may be applied and in connection with which it may be used, and that many parts of the organization herein disclosed may be modified or may have other parts substituted for them without the exercise of invention in applying the essential features and principles of this invention 30 to some other type of telephone system; and that therefore it is not intended to restrict the scope of the invention as claimed to the precise embodiment that has been described and illustrated.

40 What is claimed is:

1. The combination with a plurality of lines and an extension circuit therefor, of a finder switch for connecting said extension circuit with a calling line, sources of characteristic current, a number indicating device, and switch mechanism associated with said extension circuit and automatically operated to select various of said characteristic currents in accordance with the calling 45 line number, and to successively connect them to said indicating device to cause it to identify the calling line.

2. In a telephone system, the combination with a plurality of telephone lines and an extension circuit therefor, of a finder switch for connecting said extension circuit with a calling line, an indicating device having a plurality of operating stages, sources of characteristic current, means operated in accordance with the movement of said finder switch for selecting characteristic currents from said sources, and a sending switch associated with said extension circuit having operating stages corresponding with the operating stages of said indicating device, and

adapted to apply a selected characteristic current in each operating stage to cause a characteristic operation of said indicating device in the corresponding stage.

3. The combination with a plurality of 70 lines and an extension circuit therefor, of a finder switch for connecting said extension circuit with a calling line, a sending switch associated with said extension circuit and having an operating stage for each digit of 75 the calling line number, an indicating device having corresponding operating stages, sources of characteristic current, and means controlled in the operation of said finder switch for selecting characteristic currents 80 in accordance with the digits in the calling line number and connecting the same to said sending switch for application to said indicating device in each corresponding operating stage, whereby said device is operated 85 to indicate the number of the calling line.

4. In a telephone system, the combination with a plurality of lines and an extension circuit therefor, of a finder switch, means for moving the same to make connection 90 with a calling line, indicating apparatus associated with said extension circuit, a source of characteristic currents, current selecting mechanism associated with said extension circuit and controlled in accordance with 95 the movement of said finder switch to select certain of said characteristic currents, and a switch associated with said finder switch for combining said selected currents into a characteristic current train and transmitting 100 said train to said indicating apparatus to operate it to identify the calling line.

5. The combination with a plurality of telephone lines and an extension circuit therefor, of a finder switch for connecting 105 said extension circuit to a calling line, an indicating device adapted to produce signal indications in accordance with the digits of a calling line number, a source of characteristic currents, means controlled in the 110 operation of said finder switch for selecting currents characteristic of the various digits of a calling line number, and a sending switch associated with said extension circuit for successively applying the selected 115 characteristic currents to said indicating device to cause it to indicate the successive digits of the calling line number.

6. In a call distributing system, the combination with a plurality of telephone 120 lines and an extension circuit therefor, of a finder switch for connecting said extension circuit with a calling line, number indicating apparatus, an impulse producing means for supplying groups of different 125 numbers of impulses, impulse selecting switch mechanism associated with said extension circuit and automatically operated in the operation of said finder switch to select groups of impulses corresponding to 130

the different digits in the number of the calling line, and an impulse sending switch associated with said extension circuit for combining said selected impulse groups into a characteristic impulse train and applying the same to said number indicating apparatus to cause it to indicate the digits of the calling line number.

7. In a telephone system, the combination with a plurality of telephone lines and an extension circuit therefor, of a finder switch for connecting said extension circuit with a calling line, an indicating device having a plurality of operating stages, sources of characteristic current, means operated in accordance with the movement of said finder switch for selecting certain of said characteristic currents, and a sending switch associated with said extension circuit having operating stages corresponding with the operating stages of said indicating device and adapted to apply a selected characteristic current in each operating stage to effect the operation of said indicating device in the corresponding stage to identify the calling line.

8. In a call distributing system, the combination with a multiple brush switch having line terminals arranged in groups, of means for making one of the brushes active and moving the switch to bring the active brush into connection with a particular line terminal, a source of electrical impulses, an impulse operated indicating device, and mechanism controlled in accordance with the brush made active and the extent of movement of said switch for selecting certain of said electrical impulses and applying them to said indicating device to cause the operation of the same to indicate the position of the line terminal with which the switch makes connection.

9. In a call distributing system, the combination with a plurality of telephone lines and an extension circuit therefor, of a switch having multiple brushes to which said extension circuit is connected and line terminals divided into groups to which said telephone lines are connected, means for making a brush active and moving the same into engagement with any one of the line terminals of the associated group, indicating apparatus, a source of electrical impulses, impulse selecting mechanism set in accordance with the brush made active and the line terminal engaged, and means associated with said extension circuit for transmitting the selected impulses to said indicating apparatus to identify the calling line.

10. In a call distributing system, the combination with a plurality of telephone lines and an extension circuit therefor, of a multiple brush finder switch having a group of line terminals for each of the multiple brushes, said telephone lines terminating on

said line terminals and said extension circuit extending from said multiple brushes, tripping means for each of said brushes to render the corresponding brush active, a number indicating device, and controlling mechanism therefor associated with said extension circuit and selectively controlled in its operation in accordance with the brush tripping means operated.

11. In a telephone system, the combination with a multiple brush automatic switch having a group of line terminals for each of its brushes, of an extension circuit connected to the multiple brushes and a plurality of telephone lines terminating upon the line terminals of said switch, means for rendering active any one of said brushes and moving the same to engage an associated line terminal, and indicating mechanism associated with said extension circuit and selectively controlled by said means to give an indication in accordance with the group containing the line terminal engaged.

12. The combination with a multiple brush automatic switch having a group of line terminals for each of its brushes, of an extension circuit from said brushes, an indicating device associated with said extension circuit, means for rendering active a predetermined brush to connect with a line terminal in the associated group, and means for controlling the indication of said number indicating device in accordance with the particular brush rendered active.

13. The combination with a multiple brush automatic switch having a group of line terminals for each of its brushes, a common circuit multiplied to said brushes, individual circuits connected to said line terminals, means for rendering active a predetermined brush and moving it to connect with one of the line terminals in the associated group, indicating mechanism, and means associated with said common circuit for producing a selective indication of said indicating mechanism in accordance with the particular brush made active and the extent of movement of that brush in connecting with a particular line terminal.

14. The combination with a multiple brush switch having line terminals arranged in groups, of a circuit extending from said multiple brushes, means for making one of said brushes active and moving the switch to bring the active brush into engagement with a line terminal of the corresponding group, number indicating apparatus, and means associated with said circuit and selectively controlled in accordance with the particular brush made active and the extent of movement of the switch for operating said number indicating apparatus to indicate the number of the line terminal engaged.

15. In a call distributing system, the com-

- bination with a plurality of telephone lines and an extension circuit therefor, of a finder switch having multiple brushes serving as terminals of said extension circuit and line contacts arranged in groups upon which said telephone lines terminate, number indicating apparatus associated with said extension circuit, impulse producing means for producing groups of impulses differing from each other in the number of impulses in each group, an impulse sending switch associated with said extension circuit for applying to said number indicating apparatus successive groups of impulses, 10 one group for each digit of the designating number of the calling line, means for applying to said impulse sending switch a group of impulses corresponding to the thousands digit of the lines served by said finder switch, an impulse selecting switch, means for selectively operating the same in accordance with the finder switch brush made active in making connection with a calling line, means controlled by said impulse selecting switch for selecting and applying to said impulse sending switch a group of impulses corresponding to the hundreds digit of the calling line, an impulse selecting commutator set in accordance with the extent 20 of movement of the active brush in making connection with a calling line, means controlled jointly by said impulse selecting commutator and the aforesaid impulse selecting switch for selecting and applying 25 to said impulse sending switch a group of impulses corresponding to the tens digit of the calling line, and means controlled by said impulse selecting commutator for selecting and applying to said impulse sending switch a group of impulses corresponding to the units digit of the calling line, said selected groups of impulses being applied by said impulse sending switch in succession to said indicating apparatus to cause the same to indicate the 30 number of the calling line.
16. The combination with a plurality of telephone lines and an extension circuit therefor, of an operator's position, an indicating device at said position adapted to respond to a train of characteristic currents to indicate the digits of the number of an extended telephone line, a source of characteristic currents, and selectively controlled means associated with said extension circuit for selecting characteristic currents in accordance with the line number digits of any calling line with which said associated extension circuit is connected, combining said currents in a train, and applying said 35 train to operate said indicating device.
- In witness whereof I hereunto subscribe my name this 16th day of January, 1919.
